(57) **CLAIM**

The ornamental design for trailer for infant electric vehicle as shown and described.

DESCRIPTION

FIG. 1 is a perspective view of the trailer for infant electric vehicle according to the present invention.

FIG. 2 is a perspective view of the trailer for infant electric vehicle, which is shown in an environment of use.

FIG. 3 is a front view of the trailer for infant electric vehicle of FIG. 1.

FIG. 4 is a rear view of the trailer for infant electric vehicle of FIG. 1.

FIG. 5 is a left side view of the trailer for infant electric vehicle of FIG. 1.

FIG. 6 is a right side view of the trailer for infant electric vehicle of FIG. 1.

FIG. 7 is a top view of the trailer for infant electric vehicle of FIG. 1; and,

FIG. 8 is a bottom view of the trailer for infant electric vehicle of FIG. 1.

The broken lines shown in the figures are for the purpose of illustrating portions of the trailer for infant electric vehicle as shown in an environment of use and form no part of the claimed design.

1 Claim, 8 Drawing Sheets
